UNITED STATES PATENT OFFICE.

GEORGE W. FROST, OF MILWAUKEE, WISCONSIN, ASSIGNOR TO KOEHRING COMPANY, OF MILWAUKEE, WISCONSIN, A CORPORATION.

BUCKET-DUMP TRIP MECHANISM.

Application filed January 27, 1923. Serial No. 615,193.

To all whom it may concern:

Be it known that I, GEORGE W. FROST, a citizen of the United States, residing at Milwaukee, in the county of Milwaukee and 5 State of Wisconsin, have invented certain new and useful Improvements in Bucket-Dump Trip Mechanism, of which the following is a specification.

The invention hereof comprises certain 10 improvements in the construction of bucket controlling mechanism including dumping and restoring instrumentalities, for distributing buckets such as utilized in conjunction with what are known as concrete pavers, 15 or paving machines, in common use today. Letters Patent showing a typical construction embodying the general basic features of that hereinafter set forth, are No. 1,141,470, issued June 1, 1915, to E. H. Lichtenberg.

20 Among the novel features of the present bucket dumping and restoring devices, are the following provisions:

An arrangement and co-operation of parts intended to impart to the door or doors of 25 the bucket a perpendicular movement when the trolley which carries the bucket is moved in either of opposite directions, and in a manner which is controllable by the operator of the machine. A novel form of 30 shuttle or trip mechanism which is carried by the supporting trolley of the bucket. Peculiar door releasing and restoring or closing features included in the last mentioned mechanism. A special form of trolley construction per se, and novel operative connections between the door releasing and restoring instrumentalities, and the door itself.

In the accompanying drawings;

Figure 1 is a side view of bucket mechanism carried by a boom such as used on 40 a paving machine, certain parts including primarily the tripping dog, and the door restoring member being shown in dotted lines in position indicative of range of movement.

Figure 2 is a front view of the bucket mechanism of Fig. 1, the boom being illustrated in section.

Figure 3 is a view of door dumping and 50 releasing mechanism somewhat like that illustrated in Figures 1 and 2, but mounted upon a somewhat different construction of trolley.

Figure 4 is a sectional view showing more 55 particularly the mechanism of Fig. 3.

Figure 5 is a cross sectional view showing more clearly the mounting of the stops which limit the movement of the trolley in the direction of the mixer and effect closing of the bucket door.

Figures 6, 7, and 8 are plan sectional and end views respectively, of the shuttle device which carries the trip dog.

Figure 9 is a detail view of the stop 21 limiting the movement of the shuttle in one 65 direction.

Figure 10 is a view showing more clearly the construction of the door and its connection with the opening and closing yoke.

To facilitate an understanding of this invention, it may be noted that the boom A is one such as may be mounted upon the frame work of a concrete mixer, and is susceptible of being adjusted vertically at different inclinations in relation to the frame, 70 as well as of being swung horizontally to cover a relatively wide area of distribution, in dumping the concrete upon the subgrade with a distributing action. On this boom A which usually comprises spaced connected 80 channels, there is attached a cam 1 which functions in controlling the action of a certain trip member by which the door holding member may be released, said cam also including a feature in the form of a stop 85 or engaging member, which functions in co-operation with the door closing member to control the latter. The cam 1 may be attached to the boom A in any suitable manner.

The trolley B supports the bucket C by means of hangers 2, said trolley or carriage B is equipped with ways or guides 3, in which slides a shuttle or knock-off member 4. On the shuttle 4 at its outer or left hand 95 end is pivoted a trip dog 5, the said dog adapted at its upper end to engage the cam 1, and when so engaged the lower end or tail 5a thereof is held upright and clear of the door holding and locking member 6. The member 6 consists of a shaft transverse 100 to the trolley, equipped with rollers 7 upon its ends, and passing thru the upper end of a yoke bar 8. The yoke bar 8 is connected with a yoke 9 which is sufficiently broad 105 in its span that its sides receive therebetween the bucket C. The sides of the yoke 9 are connected at their lower extremities, as at 10, with the door 11 of the bucket C, and the degree of opening movement of the door 110

11 is adjustable and regulated by means of adjustable stops 12 on the sides of the yoke 9, which stops are capable of engagement with stop brackets 13 attached to the sides 5 of the bucket. The sides of yoke 9 are formed with openings for facilitating the adjustment of the stops 12.

Normally the holding and locking member 6 is so disposed that its rollers 7 are received 10 in a seat 14, this adjustment maintaining the door 11 locked closed.

For knocking off the member 6 to trip or throw the same from its seat position aforesaid, the trip dog 5 is employed. Normally, when the bucket C is in its receiving or charging position adjacent to the mixer, the dog 5 is inoperative to act upon the holding member 6, because the cam 1 maintains the tail or lower end of the dog 5 above the 20 plane of the member 6. When, however, the trolley B and the member C are moved outwards on the boom A, the upper end of the dog 5 passes from beneath the cam 1, and the tail of the dog 5 lowers in front of the member 6. The moving cable 15 for the trolley B is attached to the shuttle member 4, and after this cable has been operated by a suitable clutch mechanism, in an outward direction, the shuttle 4 which has a free sliding 30 movement on the trolley in the guides 3, for a few inches, engages with a stop 16, and the abutment between the parts 4 and 16 causes the trolley to move outwards until the bucket has reached a point where it is desired to 35 dump it. Thereupon the cable or pull-rope 15 is reversed, and as the dog 5 has moved so that its tail is in front of the member 6, reversal of the movement of the cable 15 initially actuates the shuttle 4 to cause impingement of the dog 5 with the member 6, unseat the latter from the seat 14, and cause it to move downwards in depending 40 guides 17 that project downwards from the carriage or trolley B. The door 11 is caused 45 to open in the above operation thru the downward movement of the yoke 9, which is supported by the member 6 and its yoke bar 8. The degree of opening movement of the door is determined by the co-operation of the 50 parts 12 and 13.

On reference to Fig. 1 especially, it will be noted that the holding or locking member 6 by which the door is maintained in its closed position, has connected thereto a restoring device which preferably comprises spaced hook links 18. These links have 55 pivotal connection with the member 6, at the lower ends of the links, the member 6 by its shaft formation constituting the pivot itself, 60 as well as a shaft on which the rollers 7 are mounted. Normally when the bucket door 11 is closed, the links 18 occupy approximately horizontal positions, as shown in Fig. 1, in dotted lines, the curved upper extremities or hook portions of the links being con-

nected together by a bolt or impingement member 19. The member 19 is capable of engaging stops 20 on the boom A adjacent to the cam 1, when the bucket C and the trolley B are brought back by action of the cable 15, 70 to the mixer to be recharged.

With the above general arrangement of parts and their construction set forth, an entire operation of the machine will be described. Assuming that in Fig. 1, the door 75 11 is closed, the holding member 6 is at its upper seating or locking position, and the restoring or door closing device 18 is engaged with the stops 20, with the dog 5 co-operating with the cam 1; we have the parts 80 in their positions as when the bucket is located at the mixer ready to be charged, or already charged with a batch of concrete to be distributed. The operator throws in certain clutch mechanism, not illustrated, to actuate the cable 15, whereupon the shuttle 4 is moved outwards, engages the stop 16 on the trolley B after said shuttle moves a few inches, and then causes the trolley to move 85 outwards on the boom A together with the shuttle. In this manner the dog 5 becomes released from the cam 1, and its tail drops in front of the member 6. At the point where the bucket is to be opened, in its 90 length of travel on the boom A, the operator throws in the clutch mechanism for reversing the cable 15, the dog 5 knocks off the holding member 6, which slides down in the guides 17, and the door 11 is thus opened as 95 an initial action involving reverse movement 100 of the shuttle 4 and sliding movement of the shuttle relatively of the trolley B. The action of the shuttle 4 in moving the dog 5 to knock off the member 6 for dumping the bucket is very quick, and then the shuttle 4 abuts with another stop member 21 on the trolley, cooperating therewith to move the 105 bucket C back toward the mixer, the door 11 retarding the outflow of the concrete and causing it to be distributed by a spreading 110 action over the subgrade. This spreading action is very well presented in U. S. Letters Patent of Lichtenberg, No. 1,411,217, issued March 28, 1922. It is notable, however, that 115 in the present construction the door 11 has a somewhat curved formation affecting in a measure the spreading function. If desired while the bucket is open, the clutch mechanism controlling the cable may again be reversed to shift the bucket outwardly along 120 the boom in a direction of movement of its dumping position as the shuttle 4 will effectively co-operate with the stop 16 under such conditions. This enables a distribution of concrete over the same area on which it has 125 been previously deposited, and thereafter the cable may be reversed a third time to carry the bucket back to the machine. Or the reversing action of the cable may take place 130 several times to impart to the bucket C a 130

back and forth or sort of reciprocating distributing action. However, when the bucket is empty, and it is desired to move it back to its charging position, the inhaul on the cable 15 is completed with the shuttle 4 acting against the stop 21 until the bucket reaches the mixer, at which time the restoring device comprising the links 18 and part 19 will have been engaged with the stops 20, and the holding or locking member 6 will have been raised and reseated in the seat 7 by the up pull on the links 17 in the door closing or restoring action.

When the trolley B reaches the limit of its inhaul movement, the dog 5 will have been engaged again with the cam 1, and the tail of the dog will be lifted clear of the member 6, rendering the dumping mechanism inactive while the bucket is at its charging position.

In Figures 3 and 4 of the drawings, a slightly modified adaptation of the invention is employed wherein parts largely equivalent to those previously set forth will be noted. It may be observed that the cam 1' in Fig. 3 is somewhat differently shaped from the cam 1 previously set forth, though functioning largely the same. However, in Figs. 3 and 4, it is notable that the stops 20' are cushioned by a spring 20'', and the outward projection of the stops 20' from the part in which it is mounted, is limited by a pin and slot connection shown at 20'''. Otherwise, the general construction of parts 35 is about the same as set forth, the mounting being somewhat different owing to the use of a different form of carriage B'. Those parts which are equivalent to the ones described previously are designated by the same general reference characters combined with prime marks, and need not be referred to in detail. Obviously, there may be a number of modifications in the specific detail construction and operation of the parts 45 as presented herein, these phases of the invention not being very material.

I contemplate using a resilient member in the form of a spring 23 between the member 6 and yoke 9, the same tending to resiliently hold the locking member 6 seated by a resilient action while the door is closed.

The trolley B will be seen to comprise a main body portion equipped with the rollers 25 and a rocking section composed of pivoted arms 26 to the ends of which are journaled the rollers 27. The rear portion of the trolley B, or that nearer the mixer is extended or canted in the direction of the mixer, being projected quite a little distance beyond the hangers 2 so that the trolley may move sufficiently toward the inner extremity of the boom to bring the bucket C well beneath the discharge chute of the mixer, or any suitable chute by which 60 the concrete is to be supplied to the bucket.

Owing to the pivotal mounting of the rollers 27 on the arms 26, and the composite construction of the trolley B, the load in the bucket C is distributed over a wide working area in respect to the draft on the boom. The arms 26 in other words are equalizing arms which automatically adjust themselves to distribute the load pressure of the bucket C and its contents, in relation to the boom, the wheels 27 working in conjunction with the wheels 25 to the above end. At times the bucket C is not loaded with absolute accuracy so far as its center of gravity when loaded is concerned, and due to this variation the equalizing trolley construction is of advantage.

The stops 20 are provided one on each of the channels which comprise the boom A, as seen best in Fig. 5, and one of the stops may or may not be a part of the cam 1, as desired. Preferably, however, one of the stops 20 is integral with the cam 1. The front end of the trolley B carries an adjustable abutment in the form of bolts 28 equipped with suitable clamping nuts 29, the head of which bolts may be adjusted so as to properly adjust rollers 19 or 19', in respect to the seat 7.

Also it is notable in reference to the bucket door 11, that the sides of the yoke 9 have a sort of loose connection with the door, as seen best at 10^a, and the door is hinged to a bracket 10^b on the bucket C at a point somewhat between the front and rear edges of the door. This construction enables the bucket to center itself in closing, in relation to the bucket opening.

The stop 21 has a combination function in that it limits the movement of the shuttle 4 in one direction, and is formed with shoulders 21^a that act as spacing means between the sides of the carriage B. A tie bolt 21^b passes thru the stop and spacer member 21. The stop means 16 really consist of vertical ribs at the outer ends of the little guideways or slots 3 which are formed in the inner sides of the trolley B. The wider portions of the shuttle, as seen best in Fig. 6 are adapted to abut with the stop means 16 in an obvious manner, the shuttle 4 having an outwardly extending lug or arm to which the dog 5 is pivoted. The ends of the cable 15 are attached to the shuttle by a clamp plate 4^a mounted on the shuttle, said ends of the cable being passed thru suitable openings and disposed in opposite directions on the body of the shuttle. The method of attaching the ends of the cable to the shuttle is not very material, because some other convenient method might be used. However, the construction employed accommodates for taking up slack in the cable when necessary, and is a good working construction in practice. The under side of the plate 4 may be serrated or roughened to

grip the cable ends more firr'y, and Figures 6 to 8 inclusive, show the arrangement just set forth.

Having thus described my invention, 5 what I claim as new, and desire to secure by Letters Patent of the United States, is:

1. In combination, a boom, a trolley mounted to travel thereon and having a seat, a dumping bucket supported by the trolley and comprising a door, a door locking member connected with the door and normally supported in the trolley seat, means operable to knock the locking member off the said seat to release the door, a restoring link connected to the door locking member, and trip means cooperating with the restoring link to close the door as an incident to the movement of the trolley on the boom.
2. In combination, a boom, a trolley adapted to travel thereon and having a seat, a dumping bucket supported by the trolley and comprising a door, a door locking member connected with the door and normally supported in the seat of the trolley, means operable to knock the locking member off of the seat to release the door, a hooked restoring link pivotally connected to the door locking member, and trip means cooperating therewith to automatically close the door as an incident to the movement of the trolley on the boom.

3. In combination, a boom, a trolley adapted to travel thereon and having a seat, a dumping bucket supported by the trolley and comprising a door, a door locking member connected with the door and normally supported in the trolley seat, means operable to knock the locking member off said seat to release the door, the last means including a shuttle movable relatively to the trolley.

4. In combination, a boom, a trolley adapted to travel thereon and having a seat, a dumping bucket supported by the trolley and comprising a door, a door locking member connected with the door and normally supported in the trolley seat, means operable to knock the locking member off said seat to release the door, and guides for receiving and limiting the movement of the locking member when knocked off its seat.

5. In combination, a boom, a trolley adapted to travel thereon and formed with a seat, a dumping bucket supported by the trolley and comprising a door, cable means for moving the trolley back and forth on the boom, a door locking member connected with the door and normally supported in the seat of the trolley, a shuttle connected to the cable and having a limited sliding movement relative to the trolley, said trolley being provided with stop means to engage the shuttle at both limits of its movement, and means actuated by the shuttle

for knocking the locking member off of the seat to release the door.

6. In combination, a boom, a trolley adapted to travel thereon and having a seat, a dumping bucket supported by the trolley and comprising a door, a door locking member connected with the door and normally supported in the trolley seat, means to co-act with the locking member to shift it from its seat enabling door opening action of the bucket, an instrumentality for pulling the locking member back on to its seat, and means on the boom to engage and operate said instrumentality.

7. In combination, a boom, a trolley adapted to travel thereon and having a seat, a dumping bucket supported by the trolley and comprising a door, a door locking member connected with the door and normally supported in the trolley seat, means to co-act with the locking member to shift it from its seat enabling door opening action of the bucket, an instrumentality for pulling the locking member back on to its seat, and a cable for moving the bucket and instrumentalities associated with the cable by which the actuating devices for the locking member are operated through action of the cable to both shift the latter from and to its seat.

8. In combination, a boom, a trolley adapted to travel thereon and having a seat, a dumping bucket supported by the trolley and comprising a door, a door locking member connected with the door and normally supported in the trolley seat, means to co-act with the locking member to shift it from its seat enabling door opening action of the bucket, a pulling device on the trolley connected to the door of the bucket to restore it to closed position, and a stationary member carried by the boom to engage the pulling device and cause it to effect said door closing action.

9. In combination, a boom, a trolley adapted to travel thereon and having a seat, a dumping bucket supported by the trolley and comprising a door, a door locking member connected with the door and normally supported in the trolley seat, means to co-act with the locking member to shift it from its seat enabling door opening action of the bucket, a pulling device on the trolley connected to the door of the bucket to restore it to closed position, and a stationary member carried by the boom to engage the pulling device and cause it to effect said door closing action, said stationary member comprising a cushion.

10. In combination, a boom, a trolley adapted to travel thereon and having a seat, a dumping bucket supported by the trolley and comprising a door, a door locking member connected with the door and normally supported in the trolley seat, means operable to knock the locking member off said

- seat to release the door, and a yoke spanning the bucket at opposite sides and forming the connection between the locking member and the door. 60
- 5 11. In combination, a boom, a trolley adapted to travel thereon and having a seat, a dumping bucket supported by the trolley and comprising a door, a door locking member connected with the door and normally supported in the trolley seat, means to 65 contact with the locking member to shift it from its seat enabling door opening action of the bucket, a yoke spanning the bucket at opposite sides and forming the connection between the locking member and door, a door closing device connected to said yoke, and means to operate the closing device when the trolley reaches a certain position on the boom. 70
- 10 12. In combination, a boom, a trolley mounted to travel back and forth thereon and having a seat, a dumping bucket supported by the trolley and comprising a door, a cable for moving the trolley, a door locking member connected with the door and normally supported in the seat of the trolley, a shuttle member connected to the cable and having a limited movement relative to the trolley, stop means on the trolley for 75 engaging the shuttle at both limits of its said movement, means actuated by the shuttle for knocking the locking member off of the seat of the trolley to release the door, a restoring element connected to the door locking member, and trip means cooperating with the restoring element to close the door as an incident to the movement of the trolley on the boom. 80
- 15 13. In combination, a boom, a trolley arranged to travel thereon, a bucket supported by the trolley and comprising an openable door, a yoke spanning the bucket and having its sides connected with said door, tripping mechanism on the trolley connected with the yoke to control opening movement of the door, and adjustable stop means intermediate the sides of the bucket and the sides of the yoke for determining the extent of opening of the door. 85
- 20 14. In combination, a boom, a trolley arranged to travel thereon, a bucket supported by the trolley and comprising an openable door, a yoke spanning the bucket and having its sides connected with said door, a locking member for holding the yoke and door in door closing position, the trolley having a seat to receive said locking member and maintain it in its door closing position, a shuttle on the trolley, means intermediate the shuttle and the locking member for knocking the latter off its seat to open the door, and a restoring device for closing the door, including links connected with the locking member, and formed with hook ends, together with a stationary part to co-operate with the hook ends of the links to upraise the latter when the trolley reaches a certain position on the boom whereby to close the door. 90
- 25 15. In combination, a boom, a trolley arranged to travel thereon, a bucket supported by the trolley and comprising an openable door, a yoke spanning the bucket and having its sides connected with said door, a locking member for holding the yoke and door in door closing position, the trolley having a seat to receive said locking member and maintain it in its door closing position, a shuttle on the trolley, means intermediate the shuttle and the locking member for knocking the latter off its seat to open the door, and a restoring device for closing the door, including links connected with the locking member, and formed with hook ends, together with a stationary part to co-operate with the hook ends of the links to upraise the latter when the trolley reaches a certain position on the boom whereby to close the door, the trolley being equipped with guides at opposite sides thereof, and the locking member having rollers to engage and operate in said guides to guide the door opening movement of the locking member when unseated and when being seated. 95
- 30 16. In combination, a boom, a trolley, a bucket on the trolley having a dumping door, a yoke receiving the bucket between its sides and having the lower ends of its sides connected to the door, and tripping mechanism on the trolley to open and close the door through operation of the yoke, the tripping mechanism including a resilient connection between one of its parts and the said yoke. 100
- 35 17. In combination, a boom, a trolley, a bucket on the trolley having a dumping door, door closing means including members at opposite sides of the bucket, and tripping mechanism on the trolley connected with the said members to close the door, and spring means intermediate the said members and the tripping mechanism providing a resilient action for maintaining the door closed substantially as set forth. 105
- 40 18. In testimony whereof I affix my signature. 110
- 45 19. GEORGE W. FROST. 115
